UNITED STATES PATENT OFFICE

2,492,889

METAL SHEET STACKING APPARATUS

James M. Royal, Chicago, Ill., assignor to Continental Can Company, Inc., New York, N. Y., a corporation of New York

Application October 22, 1945, Serial No. 623,763

13 Claims. (Cl. 214—11)

1

The invention relates generally to apparatus for handling metal sheets or other articles and primarily seeks to provide novel means for effecting magnetic selection and distribution of such sheets or articles.

An object of the invention is to provide novel means for conveying such sheets in processional order over a plurality of longitudinally spaced stacking stations and for bringing about the stacking of some sheets at one station and other sheets at another station.

Another object of the invention is to provide sheet handling and stacking means of the character stated wherein alternate sheets are alternately stacked in two individual longitudinally spaced stacks.

Another object of the invention is to provide metal sheet handling apparatus of the character stated in which there is provided a travelling belt, permanent magnet means closely overlying the belt and effective to hold a sheet against the belt and cause it to move therewith, and means for moving the magnet means away from the belt to cause the sheet being moved to fall away at a selected position.

Another object of the invention is to provide metal sheet handling apparatus of the character stated wherein the magnet moving means includes a rotary cam operating in timed relation to the travelling belt.

Another object of the invention is to provide a metal sheet stacking apparatus wherein are included two longitudinally spaced stack receivers, means normally effective to feed successive sheets into the first encountered stack receiver, and means including a feeder belt and magnet means effective to attract selected sheets to the belt to be carried thereby over said first encountered stack receiver and to release them into the other stack receiver.

Another object of the invention is to provide an apparatus of the character stated novel three-point or three position support for each sheet as it approaches a given stack receiver comprising side edge supports engaging the sheet close to its side edges, and a transversely disposed roll over which the sheet passes just prior to the falling of the trailing edge of the sheet into said receiver.

With the above and other objects in view that will hereinafter appear, the nature of the invention will be more clearly understood by reference to the following detailed description, the appended claims, and the several views illustrated in the accompanying drawings.

In the drawings:

2

Figure 1 is a side elevation illustrating a sheet contacting apparatus embodying the invention.

Figure 2 is a plan view, parts being broken away.

Figure 3 is a vertical cross section taken on the line 3—3 on Figure 1.

Figure 4 is a vertical cross section taken on the line 4—4 on Figure 1.

Figure 5 is an enlarged fragmentary vertical longitudinal section taken on the line 5—5 on Figure 2 and illustrating the manner in which the magnets are lifted and lowered.

Figure 6 is an enlarged fragmentary vertical longitudinal section taken on the line 6—6 on Figure 2, the magnets being shown as lifted and a sheet being shown in the process of falling onto the stack.

Figure 7 is a vertical cross section taken through the structure shown in Figure 6, the downward bowing of the sheet being fed being clearly shown.

Figure 8 is a detail vertical cross section taken on the line 8—8 of Figure 2.

In the example of embodiment of the invention herein disclosed, the improved sheet stacking apparatus is shown as mounted on framing 5 of a scroll shear equipment including any improved form of cutting shears of which the stationary shear 6 alone is herein shown mounted near the discharge end of a feed bed 7 over which the metal scroll or sheets are fed by any approved means (not shown).

The improved stacking apparatus preferably is supported on standards 8 which are secured as at 9 on the previously mentioned framing 5. To the upper ends of the standards 8 are secured two laterally spaced, parallel channel beams 10, and said beams are connected at their free ends by a cross frame piece 11.

An idler roller 12 extends across between the beams 10 adjacent the standard supported ends 40 thereof and is rotatably supported in bearings 13 secured to said beams. A plurality (five being shown) of feeder belts 14 pass over the idler roller 12 and extend toward the shearing station adjacent which they pass over a driver roll 15 rotatably mounted in bearings 16. The roll 15 has a gear 17 secured thereon which is driven by a gear 18 secured on a pulley shaft 19 rotatably mounted in bearings 20 having fixed thereon a sprocket 21 which is driven by sprocket and chain connections 22 from a drive shaft 23 forming a part of the scroll shear unit. See Figures 1 and 2. The drive chain is held tight by an adjustably mounted tightener roll 24.

Two pulleys 25 are mounted on the pulley shaft 55 19, and two laterally spaced, parallel belts 26

pass over said pulley and over the idler pulleys 27 mounted on the idler shaft 28 which is rotatably mounted in adjustable bearings 29 adjacent the free ends of the beams 10.

It will be apparent by reference to Figure 1 that the lower flights of the belts 26 pass over and contact with the upper portion of an idler rest roll 30 which is rotatably supported in bearings 31 secured to the beams 10.

Just beyond the idler roll 12 there is rigidly supported a cross wall 32 defining the entrant portion of a first stack receiver or compartment, and just beyond the idler rest roll 30 is rigidly mounted a cross wall 33 defining the entrant portion of a second stack receiver or compartment.

The first stack receiver is completed by a forward wall 34 depending from the beams 10 in parallel spaced relation to the wall 32 and preferably equipped with a relatively soft face piece 35 with which the sheets fed into the receiver can contact without being damaged, and two parallel side walls 36 carried by and extending below the angle iron edge supporting rails 37 and having upstanding guide wall portions 38. The rails 37 and the walls 36 are mounted at the inner ends of carriers 39 which are adjustably supported as at 40 by the beams 10.

The second stack receiver or compartment is completed by a forward wall 41 which depends from the beams 10 in parallel spaced relation to the wall 33 and preferably is equipped with a relatively soft face piece 42 to be contacted by the sheets fed into the receiver, and to parallel side walls 43 carried by and extending below the angle iron edge supporting rails 44 and having upstanding guide wall portions 45. The rails 44 are mounted on the inner ends of carriers 46 which are adjustably supported as at 47 by the beams 10. Individual floors may be provided under the first and second stack receivers, if desired, or as single skid 48 may provide a floor common to both receivers and may be supported and lifted and lowered by any approved means (not shown).

Between the flights of each belt 26 and extending over the first stack receiver and toward the shearing station is an angle member or bar 49, and said bars are connected in parallel, laterally spaced relation by cross pieces 50. Each bar 49 has three permanent magnets 51 secured as at 52 thereon to depend therefrom in the manner clearly illustrated in Figures 1 and 4 of the drawings.

Two rocker shafts 53 extend across between the beams 10 and the upper and lower flights of the belt 26 and are rockably mounted as at 54 on said beams. Each of the rocker shafts 53 has two cranks 55 projecting therefrom, and each pair of cranks is pivotally connected at the free ends with the magnet carrying bars 49 through the medium of pivot pins 56. It will also be apparent by reference to Figures 1, 2, 4 and 5 of the drawings that a crank arm 57 is mounted on the end of each rocker shaft 53 where it extends through the upright wall of one of the beams 10, and the two cranks 55 have their free ends pivotally connected with an actuator bar 58 equipped with a roller 59 at the end thereof extending toward the shearing station. It will be apparent that by reciprocating the actuator bar 58 in the direction of its length the rocker shaft 53 will be rocked and the crank arms 55 oscillated in a manner for lifting and lowering the bars 49 and the permanent magnets 51 carried thereon. It is to be understood that when the magnets are lowered

they will lie closely over the lower flights of the belts 26 and will serve to attract and hold metal sheets against said belt flights so that the sheets will be caused to move therewith, and when the magnets are lifted they will no longer be effective to attract and hold sheets against the lower belt flight.

In order to provide for the lifting and lowering of the magnets so as to bring about an alternate feeding of the metal sheets into the first and second stack receivers there is provided a cam 60 disposed in position for engaging the roller 59 at the end of the actuator bar 58 and having a concentric dwell portion 61 effective to definitely position the magnets in their raised, ineffective condition, and a raised portion or hump 62 which is effective to bring about a lowering of the magnets or in other words to place them in their effective, sheet attracting position, in opposition to the action of the retractile, magnet lifting spring 61. The cam 60 is secured on a shaft 63 which is rotatably mounted in bearing plates 64 supported by the beam 10. The shaft 63 has a large gear 65 fixed thereon, and this large gear meshes with and is driven by a small gear 66 secured on the roll 15 which drives the belts 14.

Hanger straps 68 may be attached to the upper surfaces of the beams 10 toward the free ends thereof and attached at their ends to suitable supporting standards on the shear unit to provide additional support for the stacking apparatus, if desired.

It will be apparent from the foregoing, and by reference to the several figures of the drawings that the individual metal sheets cut by the scroll shears from a continuous strip or from large sheets will be fed by the feeding devices (not shown) between the upper flights of the lower belts 14 and the lower flights of the upper belts 26, and these equipments are normally effective to feed the sheets toward and into the first stack receiver. During normal operation of the apparatus, the parts are so timed with the operation of the feeding device and the scroll shears that the actuator bar 58 yieldably held against the cam 60 by the anchored spring 68 will be operated to lift and lower the magnets 51 so as to cause the sheets to be alternately fed into the first and second stack receivers. While the actuator bar roller 59 is contacting the dwell 61 the magnets 51 will be lifted out of their effective, sheet attracting position, and a sheet will be fed into the first stack receiver, and then while said roller is engaging the cam hump 62, the magnets 51 will be held in their lowered, sheet attracting position and the next sheet will be held against the lower flights of the upper belts 26 and will be caused to move over the first stack receiver and the roll 30 and into the second stack receiver. This alternate feeding of the sheets into the first and second stack receivers will continue as long as the apparatus is operated in the manner stated.

As the sheets are fed into one or the other of the stack receivers, they are given three-point or three position support, namely, by the roll 12 or 30 across the body and trailing edge of the sheet, and at their lateral edges only by the edge supporting rails 37, thus as the leading edge of each sheet passes well beyond the respective roll 12 or 30 the unsupported central portion of said leading edge will bend downwardly and the side edges will gradually slide off the supporting rails 37 so that the sheet will fall without damage into the stack receiver. By reason of the provision of the rela-

tively soft faces 35 and 42 at the front walls of the receivers, the sheets can strike against said walls without danger of being nicked or bent.

Should it be desired to feed all sheets into one or the other of the stack receivers, this can be accomplished by a simple adjustment of the mechanism. It will be apparent that by removing the large gear 65 with the cam 60 disposed with its hump or extension 62 in engagement with the actuator bar roller 59 so as to maintain the magnets 51 in the lowered, effective position, all sheets will be attracted by the magnets and held against the lower flights of the belts 26 so as to be fed into the second stack receiver. It will also be apparent that by removing the gear 65 with the concentric dwell portion 61 of the cam in engagement with the actuator bar roller 59 so as to place the magnets 51 in their lifted ineffective position, all sheets will fall into the first stack receiver.

While one form of the invention has been shown for purposes of illustration, it is to be clearly understood that various changes in the details of construction and arrangement of parts may be made without departing from the spirit and scope of the invention as defined in the appended claims.

I claim:

1. In metal sheet handling apparatus of the character described, a travelling belt, magnet means closely overlying said belt and effective to hold a sheet against the belt and cause the sheet to move with said belt, and means for moving the magnet means away from the belt after the sheet has been moved a predetermined distance to cause the sheet to fall away and be deposited at a predetermined receiving station.

2. In metal sheet handling apparatus of the character described, a travelling belt, magnet means closely overlying said belt and effective to hold a sheet against the belt and cause the sheet to move with said belt, and means for moving the magnet means away from the belt after the sheet has been moved a predetermined distance to cause the sheet to fall away and be deposited at a predetermined receiving station, said magnet moving means including a rotary cam operating in timed relation to the travelling belt.

3. In metal sheet handling apparatus of the character described, a travelling belt, a longitudinal bar extending along said belt, a plurality of permanent magnets supported by said bar in position for overlying said belt, crank and link connections supporting said bar and shiftable to lower the magnets into close proximity to the belt to render them effective to hold a sheet against the belt and cause the sheet to move with said belt or to lift the magnets out of said effective sheet holding position, and rotary cam means for shifting said bar supporting connections in timed relation to the travelling belt so as to determine the distance of movement of sheets with the belt and the place at which said sheets will fall away from said belt.

4. In metal sheet handling apparatus of the character described, first and second longitudinally spaced stack receivers, means normally effective to feed sheets into the first receiver, and means including a feed belt and magnet means movable toward and from said belt and effective when proximate to said belt to attract selected sheets and hold them against the belt to be moved thereby over the first receiver and to release them into the second receiver.

5. In metal sheet handling apparatus of the

character described, first and second longitudinally spaced stack receivers, means normally effective to feed sheets into the first receiver, means including a feed belt and magnet means effective to attract selected sheets and hold them against the belt to be moved thereby over the first receiver and to release them into the second receiver, and means for bodily displacing the magnet means from effective sheet attracting position when it is desired to deposit a sheet in the first receiver and for again returning the magnet means to its effective sheet attracting position when it is desired to deposit a sheet in the second receiver.

15 6. In metal sheet handling apparatus of the character described, first and second longitudinally spaced stack receivers, means normally effective to feed sheets into the first receiver, means including a feed belt and magnet means effective to attract selected sheets and hold them against the belt to be moved thereby over the first receiver and to release them into the second receiver, and means for regularly and alternately displacing the magnet means from effective sheet attracting position and returning the same to effective sheet attracting position to deposit sheets alternately into said first and second receivers.

20 7. In metal sheet handling apparatus of the character described, first and second longitudinally spaced stack receivers, feed belt means effective to move sheets toward and into the first receiver, feed belt means extending over the first mentioned feed belt means the first receiver and at least to the second receiver, permanent magnets closely overlying the belt means over the first receiver and effective to attract sheets and hold them against the underlying belt means so as to cause the attracted sheets to be moved over the first receiver to the second receiver, and magnet lifting and lowering means operable at regular intervals in timed relation to the movement of the feed belt means to alternately displace the magnets from and replace them in effective position thereby to cause sheets to be deposited alternately into said first and second receivers.

25 8. Apparatus as defined in claim 7 in which the magnet lifting and lowering means comprises bar means extending longitudinally in position for supporting the magnets over the underlying belt, a pair of rocker shafts having cranks thereon pivotally connected with the bar means, cranks on said shafts disposed in parallel relation, a link connecting the last named cranks, and cam means for longitudinally shifting said link.

30 9. Apparatus as defined in claim 7 in which the magnet lifting and lowering means comprises bar means extending longitudinally in position for supporting the magnets over the underlying belt, a pair of rocker shafts having cranks thereon pivotally connected with the bar means, cranks on said shafts disposed in parallel relation, a link connecting the last named cranks, and a rotary cam having its periphery disposed for engaging and longitudinally shifting said link and having a concentric dwell portion effective to maintain the link in magnet lowered position and a raised portion effective to move the link to the magnet lifting position and then again release the same and permit it to return to the magnet lowered position.

35 10. In metal sheet handling apparatus of the character described, first and second longitudinally spaced stack receivers, feed belt means effective to move sheets toward and into the first re-

ceiver, feed belt means extending over the first mentioned feed belt means the first receiver and at least to the second receiver, magnet means closely overlying the belt means over the first receiver and effective to attract sheets and hold them against the underlying belt means so as to cause the attracted sheets to be moved over the first receiver to the second receiver, an idler roll extending transversely adjacent to the entrant end of the second receiver and with the upper surface of which the second mentioned feed belt means contacts, means for rendering said magnet means ineffective at regular intervals in timed relation to the movement of the feed belt means to cause sheets to be deposited alternately into said first and second receivers, and longitudinal sheet edge supports extending in the direction of feed from said roll and being spaced apart a distance for supporting the sheets at the lateral edges only so that the sheets are free to flex downwardly after passing a distance beyond the roll and fall freely into the second receiver between said edge supports.

11. In metal sheet handling apparatus of the character described, first and second longitudinally spaced stack receivers, feed belt means effective to move sheets toward and into the first receiver, feed belt means extending over the first mentioned feed belt means the first receiver and at least to the second receiver, magnet means closely overlying the belt means over the first receiver and effective to attract sheets and hold them against the underlying belt means so as to cause the attracted sheets to be moved over the first receiver to the second receiver, said first mentioned feed belt means passing over an idler roll extending transversely adjacent to the entrant end of the first receiver and being disposed for engaging beneath sheets which are engaged above by the second mentioned feed belt means, longitudinal sheet edge supports extending in the direction of feed from said roll and being spaced apart a distance for supporting the sheets at the lateral edges only so that the sheets are free to flex downwardly after passing a distance beyond the roll and fall freely into the first receiver between said edge supports, and means for rendering said magnet means ineffective at regular intervals in timed relation to the movement of the feed belt means to cause sheets to be deposited alternately into said first and second receivers.

12. In metal sheet handling apparatus of the character described, first and second longitudinally spaced stack receivers, feed belt means

effective to move sheets toward and into the first receiver, feed belt means extending over the first mentioned feed belt means the first receiver and at least to the second receiver, magnet means closely overlying the belt means over the first receiver and effective to attract sheets and hold them against the underlying belt means so as to cause the attracted sheets to be moved over the first receiver to the second receiver, said first mentioned feed belt means passing over an idler roll extending transversely adjacent to the entrant end of the first receiver and being disposed for engaging beneath sheets which are engaged above by the second mentioned feed belt means, longitudinal sheet edge supports extending in the direction of feed from said roll and being spaced apart a distance for supporting the sheets at the lateral edges only so that the sheets are free to flex downwardly after passing a distance beyond the roll and fall freely into the first receiver between said edge supports, an idler roll extending transversely adjacent to the entrant end of the second receiver and with the upper surface of which the second mentioned feed belt means contacts, a second set of longitudinal sheet edge supports extending in the direction of feed from the second mentioned roll and being spaced apart a distance for supporting the sheets at the lateral edges only so that the sheets are free to flex downwardly after passing a distance beyond the second mentioned roll and fall freely into the second receiver between said second set of edge supports.

13. Apparatus as defined in claim 12 in which the sheet edge supports of each set are laterally-adjustably mounted and each include an upstanding sheet edge guide and a depending receiver side wall.
